UNITED STATES PATENT OFFICE.

CHARLES A. DORAN, OF CHICAGO, ILLINOIS, ASSIGNOR TO BAUER & BLACK, OF CHICAGO, ILLINOIS, A CORPORATION OF ILLINOIS.

WASHER-SATURATING MACHINE.

1,394,153.

Specification of Letters Patent.

Patented Oct. 18, 1921.

Application filed April 1, 1918. Serial No. 225,909.

To all whom it may concern:

Be it known that I, CHARLES A. DORAN, a citizen of the United States, residing at Chicago, in the county of Cook and State of Illinois, have invented certain new and useful Improvements in Washer-Saturating Machines, of which the following is a specification.

This invention relates to a washer saturating machine in which gauze fabric or other material is treated preliminary to bleaching.

It is the object of my invention to provide a machine through which a strip or sheet of gauze fabric or other material is continuously advanced, being first saturated with water or other liquid and subsequently relieved of its excess moisture, after which it is delivered from the machine to the kiers for bleaching.

20 Further objects and advantages of my invention resides in the various combinations hereinafter described as will be apparent as the same is better understood by reference to the following specification, when 25 read in connection with the accompanying drawing illustrating the preferred embodiment thereof, in which—

Figure 1 is a plan view of the machine;

Fig. 2 is a front elevation thereof, partly 30 broken away for better illustration;

Fig. 3 is a section on the line 3—3 of Fig. 4; and

Fig. 4 is an end elevation of the machine partly broken away.

35 Referring to the drawing, 5 indicates a receptacle or vat preferably constructed of wood reinforced at the ends by frames 6, the lower ends of which provide legs 7 to support the receptacle.

40 Two shafts 8 and 9 journaled in bearings 10 on the frames 6 support rolls 11 and 12 within and adjacent the top of the receptacle. Two shafts 13 and 14 are similarly journaled in bearings 15 on the frames 6, 45 and support rolls 16 and 17 within and adjacent the bottom of the receptacle. The shaft 9 is provided with fast and loose pulleys 18 and 19 respectively which may be driven through a belt 20 from any suitable

50 source of power, a shifter fork 21 being provided to permit adjustment of the belt to either pulley. A pulley 22 on the opposite end of the shaft 9 is connected by a belt 23 to a pulley 24 on the shaft 14. Thus the 55 shafts 9 and 14 may be driven at will from

the source of power. Obviously other driving means than that described may be employed.

Within and adjacent its bottom, the receptacle 5 is provided with a plurality of 60 baffle plates 25 secured to opposite side walls of the receptacle and extending above the normal surface of the liquid in the receptacle, as determined by the liquid outlet 26 in one end of the receptacle. An inlet 27 for 65 the liquid is provided at the other end of the receptacle. The baffles 25 are provided with suitable openings through which the rolls 16 and 17 pass. The object of the baffles is to cause the liquid to follow a 70 tortuous path as it flows from the inlet 27 to the outlet 26.

Mounted in frames 28 and 29 adjacent the rolls 11 and 16 are a plurality of guide rings 30 and 31 preferably of porcelain to 75 guide the strip of fabric from the rolls 12 and 17 on to the rolls 11 and 16. As will be readily understood by reference to Fig. 4 the strip or sheet of gauze enters the top of the receptacle, passes down under the roll 16 80 at one end thereof, thence over the roll 17 and back through one of the ring guides 31 to the roll 16. Thence it continues in a zig-zag direction back and forth between the rolls to the opposite ends thereof. During 85 this movement the strip or sheet of fabric is submerged in the liquid and is washed and thoroughly saturated therewith. From the roll 17 the strip or sheet of fabric, as will be readily seen by reference to Fig. 2, passes 90 upwardly to the roll 12 and thence through one of the ring guides 30 to the roll 11. The strip or sheet of fabric passes in a zigzag direction back and forth between the rolls 12 and 11 to the opposite ends thereof, where it 95 leaves the receptacle as indicated in Fig. 4. During the movement of the strip or sheet of fabric over and between the rolls 11 and 12 the excess liquid is removed therefrom by centrifugal force and the squeezing action as the material passes over rolls 11 and 12 leaving the fabric in proper condition for further treatment in the bleaching kiers. The rolls 12 and 17 being driven from the 100 source of power as hereinbefore described 105 the fabric may be drawn through the machine continuously at a relatively high rate of speed.

From the foregoing it will be readily understood that I have perfected a machine 110

for washing and saturating strips or sheets of fabric and similar materials which is capable of handling large quantities of material in a relatively short time and may 5 be operated continuously to saturate and remove the surplus water from the fabric. The machine is particularly designed for handling strips of gauze bandage and a difficult problem in the handling of this class of 10 material is solved by the use of my machine.

Various changes may be made in the form, construction and arrangement of the parts without departing from the spirit or scope of the invention or sacrificing any of its 15 material advantages, the form hereinbefore described being merely the preferred embodiment thereof.

I claim:

1. In a washer-saturating machine, the 20 combination of a liquid receptacle, means for maintaining a constant flow of liquid with a substantially uniform level through the receptacle, means to cause said liquid to follow a tortuous path through transverse 25 channels extending across said receptacle, and means to support the material to be treated below the surface of the liquid in said receptacle and to advance said material through the liquid.

2. In a washer-saturating machine, the 30 combination of a liquid receptacle, means for maintaining a constant flow of liquid with a substantially uniform level through the receptacle, means to cause said liquid 35 to follow a tortuous path through transverse channels extending across said receptacle, means to support the material to be treated below the surface of the liquid in said receptacle and to advance said material 40 through the liquid, and means above the liquid to subsequently remove the surplus moisture from the material.

3. In a washer-saturating machine, the 45 combination of a liquid receptacle, means for maintaining a constant flow of liquid therethrough, baffles extending above the water level and secured to opposite side walls of the receptacle to cause the liquid to follow a tortuous path through the receptacle, and means to support the material 50 to be treated below the surface of the liquid in said receptacle and to advance said material back and forth in a zigzag direction therein.

4. In a washer-saturating machine, the 55 combination of a liquid receptacle, means for maintaining a constant flow of liquid therethrough, means to cause said liquid to follow a tortuous path in said receptacle, 60 driven means below the surface of said liquid to support and advance the material to be treated back and forth in a zigzag path therethrough, and means above the liquid to subsequently remove the surplus 65 moisture from the material.

5. In a washer-saturating machine, the combination of a liquid receptacle, means for maintaining a constant flow of liquid therethrough, means to cause said liquid to follow a tortuous path in said receptacle, a 70 pair of rolls spaced apart horizontally beneath the level of the liquid to support a continuous strip of material to be treated, means for driving one of said rolls to feed the strip back and forth from one roll to the 75 other, and means between said rolls for guiding the strip in its passage in one direction to cause the strip to follow a zigzag path as it advances.

6. In a washer-saturating machine, the 80 combination of a liquid receptacle, means for maintaining a constant flow of liquid therethrough, means to cause said liquid to follow a tortuous path in said receptacle, a pair of rolls spaced apart horizontally beneath the level of the liquid to support a 85 continuous strip of material to be treated, means for driving one of said rolls to feed the strip back and forth from one roll to the other, and spaced guiding rings between 90 the rolls and adjacent one of said rolls to cause said strip to follow a zigzag path as it advances.

7. In a washer-saturating machine, the 95 combination of a liquid receptacle, a pair of rolls spaced apart horizontally within said receptacle beneath the surface of the liquid, means for driving one of said rolls, and guiding means for a strip of material disposed about said rolls whereby said strip 100 is caused to follow a zigzag path as it advances back and forth through the liquid from one roll to the other.

8. In a washer-saturating machine, the 105 combination of a liquid receptacle, a pair of rolls spaced apart horizontally within said receptacle beneath the surface of the liquid and adapted to support a strip of material to be treated, means for driving one of said rolls to advance the strip back 110 and forth through the liquid from one roll to the other, and means for maintaining a constant flow of liquid through said receptacle.

9. In a washer-saturating machine, the 115 combination of a liquid receptacle, a pair of rolls spaced apart horizontally within the receptacle beneath the surface of the liquid and adapted to support a strip of material to be treated, means for driving one of said 120 rolls to advance said strip back and forth through the liquid from one roll to the other, means for maintaining a constant flow of liquid through said receptacle, and means for causing said liquid to follow a tortuous 125 path in said receptacle.

10. On a washer-saturating machine, the combination of a liquid receptacle, a pair of rolls spaced apart horizontally within said receptacle and adapted to carry a strip 130

- of material to be treated below the surface of the liquid, means for driving one of said rolls to advance the strip back and forth through the liquid from one roll to the other, and means above the surface of the liquid to withdraw the strip from the liquid and remove surplus moisture therefrom.
11. In a washer-saturating machine, the combination of a liquid receptacle, a pair of lower rolls spaced apart horizontally within said receptacle and adapted to support a strip of material to be treated below the surface of the liquid, means for driving one of said rolls to advance the strip back and forth through the liquid from one roll to the other, a pair of upper rolls spaced apart horizontally above the surface of the liquid, and means for driving one of said upper rolls to withdraw the strip from the lower rolls and to advance the strip back
- and forth from one upper roll to the other to remove surplus moisture therefrom.
12. In a washer-saturating machine, the combination of a liquid receptacle, a pair of spaced rolls within said receptacle and adapted to support a strip of material below the surface of the liquid guiding means between said rolls, means for driving one of said rolls to advance the strip through the liquid, a pair of spaced rolls above the surface of the liquid guiding means between said last named rolls, and means for driving one of said last named rolls to withdraw the strip from the liquid and to remove surplus moisture therefrom.

CHARLES A. DORAN.
